UNITED STATES PATENT OFFICE.

ALONZO LINTON BAUSMAN, OF CHICOPEE, MASSACHUSETTS, ASSIGNEE TO NATIONAL EQUIPMENT COMPANY, OF SPRINGFIELD, MASSACHUSETTS, A CORPORATION OF MASSACHUSETTS.

GRINDING-MILL.

1,035,304.

Specification of Letters Patent.

Patented Aug. 13, 1912.

Application filed August 11, 1911. Serial No. 648,529.

To all whom it may concern:

Be it known that I, ALONZO LINTON BAUSMAN, a citizen of the United States of America, residing at Chicopee, in the county 5 of Hampden and State of Massachusetts, have invented new and useful Improvements in Grinding-Mills, of which the following is a specification.

This invention relates to grinding mills 10 particularly adapted for grinding chocolate, and materials of a like or similar nature.

In grinding materials of the class referred to, the mill must be arranged for its special use for otherwise not only will the grinding 15 operation be unsatisfactory, but the material treated will be destroyed.

It should be kept in mind that a mill not built to grind material such as chocolate, etc., can not be used for this purpose since 20 the results would be to the highest degree unsatisfactory.

This invention embodies improvements 25 over the apparatus disclosed in my co-pending application filed July 21, 1910, under Serial No. 573,125.

The object of this invention is to provide 30 an apparatus which will grind materials such as chocolate, etc., in a uniform and reliable manner, and which will overcome many of the disadvantages of machines formerly used for the purpose.

Other objects of the invention will appear in the detailed description and in the claims.

While the invention has for its special 35 object the grinding of materials of a restricted class, any features of the apparatus which are new and patentable will be claimed in this, or other applications.

In the drawings forming part of this application,—Figure 1 is a front view with part in section to better show the arrangement of certain details. Fig. 2 is an end view of certain parts which show the arrangement of the valve and pump operating mechanisms. Fig. 3 is a top view of the apparatus assembled with a small part shown in section. Fig. 4 is a sectional view taken on line $x-x$, Fig. 3, showing the separate intermediate storage chambers to receive the chocolate from the pump. Fig. 5 is a sectional view taken on line $x-x$, Fig. 4, showing another view of the same. Fig. 6 is a sectional view of the pipe connections for the temperature regulating sys-

tem. Fig. 7 is a sectional view taken on line $x-x$, Fig. 8, showing the valve controlling the ports of the feed pump and the inlet ports of the feed pipes, which mechanism is preferably contained in the same casing with the pump 27 as seen in Fig. 2. Fig. 8 is a sectional view taken on the line $x-x$, Fig. 7, showing the arrangement of a valve rod with relation to the ports of the pump and the two separate feed pipes. Fig. 9 is a plan view of the essential parts 65 of the apparatus all brought into one plane for the purpose of showing the invention diagrammatically.

The invention can best be understood from an examination of Fig. 9 which shows 70 in diagrammatic plan view the essential parts of the apparatus and the course through the apparatus of the material such as chocolate which is to be ground. It will be understood, however, that the apparatus 75 whether embodied in the specific form shown or its equivalent is primarily designed to feed material, such as chocolate, to suitable grinding surfaces in a positively operating manner in which feeding operation 80 the material is measured and then forced against the grinding surfaces which are designed to grind the material as fast as it is positively fed; and since it is positively delivered, the grinding surfaces are 85 enabled to operate uniformly.

In the drawings like reference characters refer to like parts throughout the several figures.

Referring to Fig. 9 a large quantity of 90 chocolate is mixed or stored in the vessel 1 which has a communicating passage 26 to distributing chamber 32, the parts of which are controlled by the valve rod u . It will be seen by following the course of the arrow 95 in this figure that the chocolate flowing through the passage 26 enters at one side of the pump piston 33 operated by the piston rod t . By reciprocating the piston rod t and the valve rod u in a manner to be hereinafter described (but which is more or less 100 obvious from an inspection of Fig. 9) it will be seen that the movement of the pump piston will draw in a measured quantity of 105 chocolate on one side as it moves to the left in said figure, and when it moves to the right it will start to force that quantity of chocolate out through the passage y to the

storage chamber 2 at the same time drawing the chocolate in on the other side. This storage chamber is connected by continuation of the passage *y* to one side of the rotating grinding disk *e*. It will be understood that the chocolate is ground between the rotating grinding member *e* mounted between two stationary grinding members *g* and *f*. In order for the chocolate to take the course stated, it is necessary for the valve rod *u* to close the communication of the pump cylinder with the passage 26 on one side of the piston and to connect the same side with the passage *y*. This operation of the valve rod is hereinafter described together with the mechanism for bringing such operation about.

The passage *z* conducts chocolate from the other side of the pump piston to the other side of the rotating grinding member *e* in a similar manner. The rotating grinding member is keyed to a shaft *A* which is driven from a pinion on a shaft *k* in mesh with a gear *h* keyed on the shaft *A*. The shaft *k* is the driving shaft which is turned by a belt operating on a pulley *i* as indicated. The chocolate is, by the operation of the pump, valve, and rotating grinding member, ground uniformly there being a definite quantity of chocolate positively fed first to one side of the rotating grinding member and then to the other. It would be possible to feed to only one side of the grinding mechanism by stopping one inlet port of the pump with the improved results, but the duplex arrangement is preferred.

While the diagrammatic showing of the invention in Fig. 9 is fairly complete, the machine in its commercial form will now be described.

Supported on the base *a* are the uprights *b*, *c*, and *d* which, together with the base *a*, form a supporting frame for the apparatus. The driving-wheel *i* is mounted in suitable bearings in the frame, and this wheel, by suitable gearing, as indicated in Fig. 2, drives the wheel *h* which is mounted on the shaft *A*. The shaft *A* rotates in bearings *A'* mounted in supports *b* and *d*.

Mounted on the shaft *A* rotating in suitable bearings *A'* is the eccentric *m* and the cam *n*. The eccentric *m* is connected to a link 5 which is pivotally supported at 6 by the strap *p*.

In a suitable slot in the link 5 a pin *s* slides which is mounted on a bell-crank lever *r*, which lever is pivotally mounted on the frame at *q*. The bell-crank lever is rocked by the link connection with the eccentric *m* in such a manner that the pump-rod *t*, which is suitably connected to the bell-crank lever is reciprocated. At the same time the valve-stem is operated by means of the lever 7 which is pivotally mounted on the stationary frame. This lever gets its motion from

the cam *n* which operates between two rollers, as *o*, mounted on the link 9, which link is connected to the lever 7, as clearly shown in Fig. 2.

It is thought that since the link motions are so clearly shown in the drawing, more detailed description is unnecessary.

From the above description, it will be seen from Fig. 2, that as the shaft rotates, the eccentric, through the link motion described, will reciprocate the pump-rod *t*, carried by the pump 27 and a suitable bearing, see Fig. 2, while the cam *n* will reciprocate the valve-rod *u*. By properly adjusting the connections to the valve and the pump-rods the two operate at the right time with respect to each other.

The hand-wheel 25 shown in Fig. 2 is used to vary the motion transmitted from the main shaft to the piston-rod and thus vary the stroke of the piston by changing the position of the pin *s* in the slot in the link 5, as shown. This adjustment is of primary importance, for one of the main difficulties in grinding chocolate is to properly adjust the grinding surfaces. When this has once been done, it is most desirable to avoid any further adjustment. Further adjustment is avoided by regulating the feed in a most positive manner, which allows the original conditions to remain constant. By the feed-regulating means herein described, a measured quantity of material is delivered to each grinding surface for a given movement of the rotating member.

The ratio of quantity delivered to the speed of the grinding surfaces may be changed by regulating the feeding means. When the proper ratio has been obtained, it may be kept absolutely constant.

Referring to Fig. 7, the chocolate, or similar material which is to be ground leaves the storage or mixing receptacle 1 (see Fig. 3) by passage 26, enters through the passage 8 and when the valve is in the position shown, it passes to the right-hand port 9 and enters the pump cylinder. In this position of the valve the piston of the pump 27 would be traveling from right to left so that the chocolate would be driven from the pump through the left-hand port 9 to the chamber 3, and be drawn in through the right-hand port 9 to the pump cylinder. The pump piston therefore drives the chocolate out one port 9 while it sucks it through the other port 9 and the pump is full all the time. The chocolate is thus first forced through the opening *x* into the chamber 3 (see Fig. 4) and then through the opening *v* to the chamber 2. This operation is continued as long as desired.

It will be seen that the continued operation of the pump 27, as described, will force a measured quantity of chocolate first into the chamber 3 and then into the chamber 2,

the quantity going into one chamber being positively measured and equal in volume to the quantity going into the other chamber.

From the chambers 2 and 3, the chocolate 5 is forced to the opposite sides of the grinding mill through the pipes *z* and *y* respectively. It is important that the material fed to each side of the grinding mill by means of this apparatus be positively measured and exactly the same in amount.

It is plain that by the arrangement shown, the pressure of the fluid entering the mill will be the same on each side of the rotating grinding surfaces.

15 In Fig. 1, the grinding mill is shown as consisting of two stationary members *f* and *g* and an intermediate rotating member, as *e*, the rotating member *e* having both of its faces provided with grinding surfaces, and 20 the inner face of both members *f* and *g* being provided with grinding surfaces. The rotating member *e* is mounted on the shaft *A* and is rotated with the shaft *A*. The spring 4 is provided for allowing the member *f* to yield when necessary.

25 A suitable mounting is indicated in the drawing which is similar to the mounting shown and described in my co-pending application Serial No. 573,125.

30 The chocolate is fed to each side of the grinding mill, as described, and leaves the grinding mill at the circumference of the grinding surfaces in any suitable manner.

35 The pipes 2' and 11 indicate a temperature regulating system which it is necessary to use in connection with applicant's invention, for as the chocolate is fed from the container 1 through the pipes of the apparatus, it must be kept heated so that it will 40 flow freely to the grinding surfaces.

45 The grinding surfaces themselves must be cooled by suitable means so that the chocolate being ground will not become caked in the mill and thus destroy the grinding surfaces and render the device inoperative until cleaned.

50 The pipes through which the chocolate passes are shown jacketed in the drawing, as are also the two stationary grinding members. It is thought that the drawing 55 sufficiently discloses applicant's temperature regulating system, and detailed description thereof is unnecessary.

It can be seen from Figs. 1, 2 and 9 that 60 the shaft *A* mounted in bearings *A'* is positively connected with the rotating member of the grinding mill, with the controlling valve of the feed pump and with the piston rod of the feed pump, each carried by said pump 27. Thus it is clear that to operate the apparatus successfully, a suitable speed for the shaft *A* must be chosen. This speed must be chosen primarily so that the rotating member *e* of the mill proper will have 65 the right operation. The feed may then be

controlled by regulating the link motions and after the apparatus has been once positively regulated, it will operate in a fixed and certain manner.

It has been found by experiment that if 70 the chocolate is fed to the grinding surfaces by a pump and branch pipe connections, that the fluid will not flow equally to each side of the mill, such as applicant shows. The reason for this seems to be 75 that where the fluid is forced into a single pipe and led from that pipe through branches to the two sides of the grinding mill, even with the most careful designing, the pressure of the fluid will vary in the 80 different pipes, and therefore one side of the mill will receive more material than the other. This makes an uneven operation and is most objectionable. By means of applicant's apparatus, where a measured quantity of chocolate or other similar material 85 is fed to each side of the mill in a positive manner, the operation must necessarily be equal and uniform on each side of the mill, and therefore the quantity of material 90 which may be ground in a day's operation is greatly increased, not only because the material is ground in a uniform manner but because the apparatus can be adjusted positively to grind the material in a certain 95 way, and having once started the apparatus working, the likelihood of stoppage for any cause is greatly diminished by applicant's improvements.

The capacity of this apparatus for refining chocolate, that is the weight of chocolate delivered per hour, is greater than in any other known apparatus.

The capacity of the apparatus is controlled by the specific feeding means, since 105 the material refined is measured and forced through the mill in a positive manner. The apparatus may thus be depended upon to deliver its full capacity every working day.

What I claim, is:—

1. In a grinding mill, two stationary grinding members, a rotatable grinding member mounted intermediate said stationary grinding members having a grinding surface on each side thereof, and uniformly 115 operative means to positively and uniformly feed to each side of the rotating member material to be ground in exact equal portions under pressure.

2. In a chocolate grinding machine, the 120 combination with mechanism having surfaces suitable for grinding chocolate, of a uniformly positively and successively operative feeding device comprising means to measure quantities of chocolate to be 125 ground, to positively force said measured quantities successively into contact with the grinding surfaces to insure a uniform product therefrom.

3. In a chocolate grinding machine, the 130

combination with mechanism having surfaces suitable for grinding chocolate, of a uniformly positively and successively operative feeding device comprising means to 5 measure quantities of chocolate to be ground, to positively force said measured quantities successively into contact with the grinding surfaces, together with operative controlling mechanism for said feeding device to control the capacity thereof to insure 10 a product of the desired quality from said grinding surfaces.

4. In a grinding mill, means to grind chocolate comprising a rotatable member operating between two stationary members, a chocolate feeding device to feed the chocolate to each side of said rotatable member comprising a positively and uniformly operative feed device operating to first feed a 15 measured quantity of chocolate to one side of the rotatable member, and on the next stroke to feed the same measured quantity of chocolate to the other side of the rotatable

member to insure a uniform feed to the grinding means, and positive driving means 25 between the rotatable member and the feed device whereby the rotatable member operates in a chosen capacity ratio with the feed device.

5. In a grinding mill, two stationary 30 grinding members each having a grinding surface on one face, a rotatable grinding member mounted intermediate said stationary grinding members and having a grinding surface on each side thereof, means to 35 insure a uniformly ground product from both sides of the rotatable member comprising feeding mechanism to positively force an equal quantity of material for grinding to each side of the rotatable grinding member. 40

ALONZO LINTON BAUSMAN.
